UNITED STATES PATENT OFFICE

2,176,729

LUMINAIRE

Henry E. Butler, Scotia, N. Y., assignor to General Electric Company, a corporation of New York

Application December 14, 1937, Serial No. 179,700

5 Claims. (Cl. 240—25)

My invention relates to luminaires and more particularly to multiple lamp luminaires.

One object of my invention is to provide an improved structure for supplying current to the auxiliary lamp in such luminaires.

For a better understanding of my invention, together with other and further objects thereof, reference is had to the following description taken in connection with the accompanying drawing, 10 and its scope will be pointed out in the appended claims.

In the accompanying drawing, Fig. 1 is a vertical sectional view through the center of a luminaire having a main lamp and an auxiliary lamp together with my improved means for supplying current to the auxiliary lamp; and Figs. 2, 3, 4, 5, and 6 are enlarged fragmentary views of the luminaire illustrating elements and modifications of my invention.

Referring to the drawing in detail, Fig. 1 discloses a luminaire comprising a base 10, a globe 11, and a canopy 12. These elements are preferably made of a refractory material such as glass, but may be made of any other translucent or transparent material such as, for example, the synthetic resins of the urea formaldehyde group. The base 10 is mounted on a post 13, only the top of which is shown. The globe rests on the base, and the canopy rests on the globe. A main lamp 14 with its socket 15 is supported by the base 10 through U-shaped brackets 16 and 17, which are attached to said base, and an adjustable frame 18 to which the socket 15 is attached. The frame 18 may be vertically moved relatively to the brackets 16 and 17, and may be clamped thereto by thumb screws 19. An auxiliary lamp 21, together with its socket 22, is mounted in the canopy 12 by means of a bail 23. This bail is attached to the socket 22 and is drawn up into the end of the canopy by means of a pinnacle 24 to which is attached a stud 25, which projects through the canopy and is threaded into the bail 23.

Current is conducted to the main lamp 14 in the usual manner by conductors 26 and 27 attached to terminals 28 on the socket 15. Current to the auxiliary lamp 21, however, is, in accordance with my invention, carried through a second circuit including conductors attached to the inner surface of the globe and to the canopy. This circuit may be traced from supply circuit conductors 30 and 31, which project through the base 13 into the globe 11 and are respectively connected to terminals 32 and 33 which are supported respectively on the brackets 16 and 17. Re-

silient metal clips 34 and 35 are attached to the brackets 16 and 17, respectively, and project downwardly into the neck portion of the globe 11 where they engage the conductors 37 and 37a attached to the inner surface of the globe. Fig. 2 is an enlarged fragmentary view illustrating the engagement of the clip 34 with the conductor 37 on the inner surface of the globe.

The conductors 37 and 37a which carry the current from the clips 34 and 35 are preferably 10 of a metallic foil, as indicated more clearly in Fig. 5, or of a metallic mesh 38, more clearly indicated in Fig. 6, which is attached to the inner surface of the globe in any convenient manner. It is preferred to cement or glue these conductors to the inner surface of the globe so as to extend from the neck portion of the globe to the upper flange 39. Similar conductors 40 and 41 extend along the inner surface of the canopy from the lower flange up into the dome 20 portion thereof. The current is transmitted between the canopy and globe conductors by means of resilient S-shaped clips 42 and 43 made of resilient metal, such as hardened copper, for example, which engage the flange of the globe and 25 resiliently engage the conductors 40 and 41 on the canopy when the latter is mounted upon the globe. Current to the auxiliary lamp socket 22 is carried from the conductors 40 and 41 through terminal clips 44 and 45 which are 30 pressed against the inner surface of the canopy when the pinnacle 24 and its stud 25 is turned to draw the bail 23 upwardly. Fig. 3 is an enlarged fragmentary view illustrating the clip 44 in engagement with the conductor 40.

In the luminaire shown in Fig. 1, the canopy 12 is held in place on the globe 11 by springs 46 and 47 attached to the upper ends of the ornamental posts 48 and 49, any number of which may, of course, be used. The springs 46 and 40 47 press the canopy downwardly against a packing ring 51 resting on the globe surface and in this position a good contact is established between the clips 42 and 43 with the conductors 40 and 41. A release of the clips 46 and 47, however, 45 makes it possible to remove the canopy together with the auxiliary lamp 21 without the necessity of touching the connections between the canopy and globe. Fig. 4 is an enlarged fragmentary sectional view of the globe and canopy at this 50 point and illustrates the manner in which the clip 43 engages the conductors 37a and 41 while it is supported by the globe flange 39.

Fig. 6 illustrates one modification of my invention. The conductor in this instance is a fine 55

wire mesh which will constitute a minimum obstruction to light projecting through the globe, and will be practically invisible. This illustration of a conductor which will cause a minimum 5 of shadow on the glass globe is merely by way of example. Many other forms of conductors within the scope of this invention, which may be equally efficient for this purpose, will occur to those skilled in the art. The invention is, furthermore, applicable not only to new luminaires but may with equal facility be applied to old 10 single lamp luminaires. The auxiliary lamp and the conductors with the necessary clips can be installed without any structural changes in the 15 glassware nor interference with the main lamp.

What I claim as new and desire to secure by Letters Patent of the United States is:

1. In a luminaire the combination of a globe, a canopy therefor, a lamp mounted in said canopy, 20 means for supplying current to said lamp including current conductors cemented to the inner surfaces of said globe and canopy, and cooperating terminal means between said canopy and globe arranged to make surface contact with said 25 conductors and to conduct current from said globe to said canopy when said canopy is in its predetermined position upon said globe.

2. In a luminaire, the combination of a refractory casing comprising a plurality of elements in 30 adjacent relation to each other, a lamp attached to one of said elements, means for supplying current to said lamp including a current conductor in contiguous relation with the wall of said element, a current conductor contiguous with the 35 wall of an adjacent element of said casing, a resilient conductor contacting said contiguous conductors of said adjacent elements at the juncture of said elements to establish a current conducting path therebetween.

3. In a luminaire, the combination of a refractory globe and canopy, a lamp in one of said elements, and means for conducting current to said lamp including a current conductor in contiguous relation with the wall of said globe, a conductor 5 in contiguous relation with the wall of said canopy, a resilient contact element contacting said conductors at the juncture of said globe and canopy arranged to establish a current path between 10 said globe and canopy, and resilient contact means between said lamp and said contiguous conductor to transmit current to said lamp.

4. In a luminaire the combination of a base, a globe resting on said base, a canopy resting on 15 said globe, a lamp socket rigidly mounted in said canopy, and means for carrying current to said socket including conductors cemented to the inner surface of said globe extending along the surface parallel to the axis thereof, conductors on the inner surface of said canopy extending 20 parallel to the axis thereof, and resilient clips contacting the conductors of said globe and the conductors of said canopy respectively to establish a circuit between the conductors of the globe and canopy respectively.

5. In a luminaire the combination of a base, a lamp socket mounted in said base, a globe resting on said base, a canopy resting on said globe, an auxiliary lamp socket mounted in said canopy, conductors extending along the surfaces of said 30 globe and canopy respectively, resilient contact means for making surface contact with the conductors of said canopy and the conductors of said globe respectively, terminal means on said auxiliary lamp socket for connecting the canopy 35 conductors to said socket, and resilient terminal means in said base for connecting said globe conductors to current terminals in said base.

HENRY E. BUTLER.
